CLAIM

The ornamental design for an indoor antenna, as shown.

DESCRIPTION

FIG. 1 is a top and front perspective view of an indoor antenna showing my new design;

FIG. 2 is a front elevational view thereof;

FIG. 3 is a left side elevational view thereof;

FIG. 4 is a top plan view thereof;

FIG. 5 is a bottom plan view thereof;

FIG. 6 is a right side elevational view thereof; and

FIG. 7 is a rear elevational view thereof.

The present invention relates to an indoor antenna having a central dish.
